[57] CLAIM

The ornamental design for a disc-type data file, substantially as shown and described.

DESCRIPTION

FIG. 1 is a perspective view of the disc-type data file, with legs and with recess for a circuit board;

FIG. 2 is a side elevational view of one side of the data file of FIG. 1;

FIG. 3 is a side elevation view of the other side of the data file of FIG. 1;

FIG. 4 is an overhead plan view of the data file of FIG. 1;

FIG. 5 is a bottom plan view of the data file of FIG. 1;

FIG. 6 is a front elevational view of the data file of FIG. 1;

FIG. 7 is a rear elevational view of the data file of FIG. 1;

FIG. 8 is a perspective view of a modified form of the data file of FIG. 1, shown without legs and without the circuit board recess.

FIG. 9 is a perspective view of a further modified form of the data file of FIG. 1, shown without the circuit board recess.

FIG. 10 is a side elevation view of the embodiment of the data file shown in FIG. 9;

FIG. 11 is an overhead plan view of the embodiment of FIG. 9;

FIG. 12 is a bottom plan view of the embodiment of FIG. 9;

FIG. 13 is a front elevational view of the embodiment of FIG. 9; and

FIG. 14 is a rear elevational view of the embodiment of FIG. 9.

The bottom view of the data file shown in FIG. 8 corresponds to that shown in FIG. 5, but without the four legs.
